UNITED STATES PATENT OFFICE.

CHARLES POPE, OF SYRACUSE, NEW YORK.

IMPROVEMENT IN APPARATUS FOR EVAPORATING SALINE LIQUORS.

Specification forming part of Letters Patent No. 27,153, dated February 14, 1860.

To all whom it may concern:

Be it known that I, CHARLES POPE, of the city of Syracuse, in the county of Onondaga and State of New York, have invented a new and useful Improvement in Apparatus for the Manufacture of Salt; and I do hereby declare the following to be a full, clear, and exact description of the construction and operation of the same, reference being had to the annexed drawings, making part of this specification.

The nature of my invention consists in so constructing arches in which kettles are set for boiling brine in the manufacture of salt that a current of heated air be conducted from the sides and surroundings of the arch to the margin of the kettles and discharged over the brine, the same being effected by first placing hollow angle-pieces between the kettles; second, by making the arms of the kettles hollow; third, by making an air-passage on each side of the arch communicating with the hollow angle-pieces and the hollow arms of the kettles.

In the drawings, Figure 1 represents a "salt block" having a line of kettles set in an arch, the fire-place A in front and the chimney B in rear. Fig. 2 represents the walls of the arch before the kettles are set, the center space, C, being for the fire and the kettles, and the side spaces, D D, being air-passages. Fig. 3 shows an edge view of one of the angle-pieces; Fig. 4, a perspective view of the same; Fig. 5, a view of one of the kettles having hollow arms.

To make and use my invention, construct the arch of stone or brick, the two walls E E forming the fire-flue C, connecting with the chimney in the rear and supporting a tier of kettles, usually in boiling brine at these salines numbering fifteen to twenty. Outside of the arch, and upon either side, erect an additional wall, F F, forming an air-chamber, D D. At the front of the air-chambers make an opening, G G, through which the chambers D D may receive a supply of air. Cast the kettles H in the usual manner and form, making the arms I hollow.

In order to fill the spaces over the arch and between the kettles, construct the "angle-pieces" J of cast or wrought iron or of brick material, and hollow, as shown at K. Place these pieces upon the arch in such a manner that the opening K shall communicate with the air-space D at the side of the arch, and the point L project between the kettles midway where it meets the corresponding point of the one on the opposite side of the arch. In setting the angle-pieces between the kettles, place the opening O in each above the margin of the kettles, as shown at P. In setting the kettles in the arch, let them rest by the arms upon the side walls in the usual manner, having the hollow of the arms communicating with the air-spaces D.

The operation is as follows: On the arch becoming heated, the air in the side spaces, D D, is warmed by the waste heat conducted through the walls of the arch, and, rising, passes upward through the hollow angle-pieces and the hollow arms of the kettles, and is discharged over the brine in the kettles, thereby assisting evaporation by absorbing the steam and carrying it rapidly away from the kettles.

What I claim as my invention, and desire to secure by Letters Patent, is—

1. The hollow angle-pieces, constructed and arranged substantially as described, and for the purpose set forth.

2. Making the arms of the kettles hollow, as set forth, and for the purpose stated.

3. Combining the hollow angle-pieces with the air-spaces D upon the sides of the arch, when so arranged that heated air may pass from the spaces upward through the angle-pieces and be discharged over the boiling liquid in the kettles, as set forth.

CHAS. POPE.
